(57) **CLAIM**

The ornamental design for a pet treat, as shown and described.

DESCRIPTION

FIG. 1 is a front, top, and left perspective view of a first embodiment of a pet treat according to the new design; FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front, top, and left side perspective view of a second embodiment of a pet treat according to the new design;

FIG. 9 is a left side elevation view thereof;

FIG. 10 is a right side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines shown FIGS. 1–14 illustrate portions of the pet treat that form no part of the claimed design. The striped shade lines and sporadic shade lines shown in FIGS. 8–14 represent a contrasting appearance.

1 Claim, 8 Drawing Sheets
